UNITED STATES PATENT OFFICE

JAMES D. CARR, OF DETROIT, MICHIGAN, ASSIGNOR TO PITTSBURGH REFLECTOR COMPANY, OF PITTSBURGH, PENNSYLVANIA, A CORPORATION OF NEW JERSEY

ELECTRIC LIGHT STRIP

Application filed June 13, 1928. Serial No. 284,961.

My invention relates to a new and useful improvement in an electric light strip adapted as a support for electric light bulbs and reflectors particularly used in illuminating 5 show windows and for other display purposes.

It is an object of the present invention to provide a strip of this class whereby access to the wiring extending longitudinally thereto 10 of may be easily and quickly had.

It is another object of the invention to provide an electric light strip of this class which may be standardized so that it becomes no longer necessary to construct the light strip 15 to order for the special jobs.

Another object of the invention is the provision of a light strip of this class having a plurality of outlet openings indicated thereon which may be easily and quickly placed 20 in condition for use.

Another object of the invention is the provision of an electric light strip of this class which may be economically constructed and which will be durable and most efficient in 25 use.

Other objects will appear hereinafter.

The invention consists in the combination and arrangement of parts hereinafter described and claimed.

30 The invention will be best understood by a reference to the accompanying drawing which forms a part of this specification and in which

Fig. 1 is a perspective view of the invention with a part broken away.

Fig. 2 is a sectional view taken on line 2-2 of Fig. 1.

Fig. 3 is a fragmentary longitudinal sectional view of the invention.

40 Fig. 4 is a perspective view of a corner piece used in the invention.

Fig. 5 is a fragmentary sectional view of the invention illustrating the adjoining of abutting strips.

45 The invention comprises a tubular member

through which wires 17 and 18 are projected, these wires being adapted for electrical connection to the socket 16 in which the light bulbs and upon which the reflectors are mounted. This tubular member comprises a 50 pair of overlapping channel-shaped members, one of which comprises the side walls 10 and 11 and the base 9, and the other of which comprises the side walls 12 and 13 which overlap the side walls 10 and 12, the base 14 connecting the side walls 12 and 13. Knock-out plugs 15 are indicated on the base 14 so that when these plugs are knocked out the socket 16 may be mounted in the opening thus formed. An end cap 19 serves as a closure 55 for one end of the tubular member and a cap 20 having the opening 21 formed therein for the passage of the wires therethrough serves as a closure for the opposite end.

By forming this tubular member of the 60 separable sections access to the wires is easily and quickly had and the cost of original installation is reduced to a minimum as the wires may be very quickly extended longitudinally of the tubular member and the 65 necessary connections made to the sockets 16. By providing the knock-out plugs 15 in one of the sections of the tubular member it becomes possible to standardize the material 70 which is used for constructing these light strips as the knock-out plugs are so located that they will determine the distance from center to center of the various light sockets so that the same stock of material may be used 75 for different jobs and in different locations.

When it is desired to span a long distance, and it becomes necessary to use several lengths of the strip, the ends may be abutted together and secured in position by the sleeve 22 which is held thereon by suitable set 80 screws.

In Fig. 4 I have shown an L-shaped arrangement whereby the strip may be used for making a turn, the telescoping arrangement of the sections being retained in mak- 85 90

ing the turn, as well as in the straight lengths.

While I have illustrated and described the preferred form of my invention, I do not 5 wish to limit myself to the precise details of structure shown, but desire to avail myself of such variations and modifications as come within the scope of the appended claims.

Having thus described my invention what 10 I claim as new and desire to secure by Letters Patent is:

1. A combined electrical conduit and outlet unit comprising a pair of relatively long, continuously extending members adapted to 15 be inter-engaged to form a wire conduit, one of the members constituting a base, the other member having knock-out plugs formed therein, and electrical outlet members in openings formed in the last-mentioned member, said member being effective for supporting and 20 spacing the outlet members prior to positioning on the first-mentioned member.

2. A combined electrical conduit and outlet unit comprising a pair of relatively long, continuously extending sheet metal members 25 adapted to be interengaged to form a wire conduit, one of the members constituting a base, the other member having knock-out plugs formed therein, and electrical outlet 30 members in openings formed in the last mentioned member, said member being effective for supporting and spacing the outlet members prior to positioning on the first-mentioned member.

3. A combined electrical conduit and outlet unit comprising a pair of relatively long, continuously extending sheet metal members adapted to be interengaged to form a wire 35 conduit, one of the members constituting a base, the other member having knock-out plugs formed therein, and electrical outlet members in openings formed in the last mentioned member by removal of knock-out plugs, said member having bent-up flanges whereby 40 the same is relatively stiff and is effective for supporting and spacing the outlet members prior to positioning on the first-mentioned member.

4. A combined electrical conduit and outlet 50 unit comprising a pair of relatively long, continuously extending sheet metal members adapted to be interengaged to form a wire conduit, one of the members constituting a base, the other member being bent to channel-like form and having a face with knock-out plugs formed therein and bent-up flanges 55 extending from the face and adapted to engage the base member, and electrical outlet members in openings formed in the channel-like member by the removal of the knock-out 60 plugs, the outlet members having portions projecting into the channel-like member, said projecting portions being of less depth than the flanges, and the channel-like member being sufficiently stiff and strong to support 65

and space the outlet members prior to positioning of the channel-like member on the base member.

In testimony whereof I have signed the 70 foregoing specification.

JAMES D. CARR.
